UNITED STATES PATENT OFFICE

JAMES W. DAWSON AND FRANK A. GARRIGAN, OF BELVIDERE, ILLINOIS, ASSIGNEES TO
NATIONAL SEWING MACHINE COMPANY, OF BELVIDERE, ILLINOIS, A CORPORATION
OF ILLINOIS

ELECTRICALLY LIGHTED SEWING MACHINE

Application filed March 12, 1931. Serial No. 521,942.

This invention relates to electrically lighted sewing machines.

The main object of the invention is to provide a lighting device which is positioned on the machine so as to efficiently illuminate the stitch forming mechanism and bed plate of the machine. Another object is to provide means for conveniently mounting the lighting device on the overhanging arm of the machine, and in such position beneath the arm that the rays of light and heat from the lamp will not annoy the operator, and the presence of the lighting device as a whole will not inconvenience the user.

An advantage of the invention is the fact that the wiring for supplying current to the lamp may be entirely concealed within the overhanging arm and upright standard of the machine.

Further objects and advantages will appear as we proceed with our specification.

In the drawing:

Fig. 1 is a side elevation of a sewing machine head embodying our invention.

Fig. 2 is an enlarged transverse vertical sectional view of a detail, taken on the line 2—2 of Fig. 1.

Fig. 3 is an enlarged transverse vertical section taken on the line 3—3 of Fig. 1.

Fig. 4 is a plan view of the lighting device, partly in section, and with the reflector broken away to show the lamp.

Fig. 5 is a bottom view of the lighting device.

In that embodiment of the invention shown in the drawing, the bed plate is indicated at 10 and mounted thereon is a conventional upright standard 11 with overhanging arm 12. The sewing mechanism constitutes no part of the present invention and therefore need not be described in detail.

The bottom wall of the overhanging arm 12 is cut away as indicated at 13 in Figs. 1 and 3 to form an elongated slot for the purpose of accommodating the lighting device of the present invention when the same is in normal position, partially within the arm.

The lighting device comprises a lamp 14 mounted in a socket 15 which has a rearwardly directed extension 16 with bifurcated

ends 17. A switch button 18 extends laterally from the socket 15. A tubular reflector 19 having a closed rounded forward end 20, is adapted to fit over the lamp 14 and on the forward end of the socket 15. The rearward end of the reflector fits against the shoulder 15' formed on the socket 15 so that the exposed surfaces of the socket and reflector are substantially flush. The reflector 19 is preferably provided with a plurality of ventilator slots 21 in its upper wall and an elongated slot 22 in its lower wall below the lamp 14.

On the lower wall of the overhanging arm 12 is a depending stud 23 which may be integral with the arm 12 or secured thereto in any desired manner. The flat sides of the stud 23 fit between the ends 17 of the lighting device which is pivotally secured to said stud by a screw 24 which extends through apertures in the arms 17 and stud 23. Wiring 25 for the lamp 14 extends upwardly from the rear end of the socket between the arms 17 through the recess 13 into the hollow arm 12 to the rear wall of the upright 11 where it is connected to a socket 26 indicated in dotted lines in Fig. 1.

When the lighting device is in its normal position as shown in Fig. 1, its forward end 20 is slightly raised and the upper portion 80 of the substantially horizontally disposed light fits into the slot 13. In this position the rays of light which pass through the opening 22 in the reflector 19 will be directed downwardly and slightly forwardly toward 85 the stitch forming mechanism 27.

By reason of its pivotal connection the lamp may be moved to the dotted line position shown in Fig. 1, but normally the lamp is inconspicuous and out of the way of the 90 operator. Its location midway between the sides of the overhanging arm is of advantage because the rays of light are uniformly distributed over the bed plate and efficiently directed toward the stitch forming mechanism. 95

Changes may be made in details of construction without departing from the scope of our invention and we do not intend to be limited to the exact form shown and described except as set forth in the appended claim. 100

We claim:

The combination of a sewing machine having a bed plate, upright standard, overhanging arm and stitch forming mechanism, the lower wall of the arm being slotted longitudinally of the arm, with an electric lighting device pivotally mounted on the lower wall of the overhanging arm at the rearward end of the slot, said lighting device comprising an electric lamp, a socket for holding the lamp, a substantially tubular reflector closed at one end and of slightly greater diameter than said slot, mounted on the socket and enclosing the lamp, said reflector normally engaging the sides of the slot in the arm and having ventilator slots in its upper wall communicating with the interior of said arm and an elongated relatively narrow slot in its wall beneath the lamp, where the ventilated lamp is invisible to the user and rays of light are normally cast only upon the bed plate and stitch forming mechanism.

In testimony that we claim the foregoing as our invention, we affix our signatures, this 23 9th day of March, 1931.

JAMES W. DAWSON.
FRANK A. GARRIGAN.
